ATTORNEY.

UNITED STATES PATENT OFFICE

CHARLES A. FOYER, OF CLEVELAND HEIGHTS, OHIO

LIFTING JACK

Application filed January 16, 1931. Serial No. 509,071.

This invention relates to lifting jacks for automobiles and other vehicles and more specifically to lifting jacks permanently secured to a convenient point on the vehicle.

5 It especially comprises an improvement on the structures described in my application Serial No. 348,550 filed March 20, 1929.

One of the objects of my invention is to provide a permanent jack for vehicles, the operation of which will be attended with a minimum of trouble and its use with a minimum of weight and expense. A further object consists in reducing the size without diminishing the strength of the jack to the end that adequate clearance may be provided for the vehicle when the jack is closed and not in use.

Many attempts have been made to provide such lifting jacks as permanent fixtures for automobiles, but their weight, size and expense have prevented their practical use particularly in view of the modern constructions which are very low to the ground.

While in the annexed drawing only the preferred form of my invention is shown, similar uses and corresponding parts are within the contemplation of my invention. For a detailed view of the preferred construction reference may be had to the accompanying drawing in which:

Figure 1 is a vertical longitudinal section through one of my improved jacks showing the jack in its contracted position, this view being taken on the line 1—1 of Figures 3 and 4;

Figure 2 is a view similar to that of Figure 1 but showing the jack in its partially extended position;

Figure 3 is a vertical end elevation showing the end of the screw adapted for connection to a wrench by which the jack is actuated; and

Figure 4 is a vertical transverse section of the jack in its partially extended position, this view being taken on the line 4—4 of Figure 1.

The invention in general comprises two pairs of toggle arms 2 and 2a pivotally joined at a common center by U-shaped end members 3 and 4. The opposite ends of the

toggle arms are secured pivotally to the ends of bottom and top members 5 and 6. The end member 4 provides a bearing for the driving end of the screw 7 while the end member 3 is threaded to engage the threaded end of the screw.

The toggle arms 2 and 2a and the bottom and top members 5 and 6 are preferably formed of lengths of channel iron. The arms 2 and 2a are made of different width channel so that one arm may completely enclose the other. Likewise, the members 5 and 6 are made of channel having different widths so that if desired the upper and lower members may likewise respectively enclose and be enclosed. In this manner, it will be observed that a housing is provided for the screw 7 which in the closed position requires a very little more space than the diameter of the screw.

As will be apparent from the drawing, the arms 2 are pivotally secured to the top member 6 by the rivets 8 and in a similar manner the arms 2a are pivotally secured to the base channel 5 by similar rivets through the opposite sides of the channel. The relatively opposite ends of the arms 2 and 2a are characterized by the outwardly curved flares 2b and 2c for purposes presently to be described.

The arms 2 and 2a severally consisting of strips of channel pivotally secured to the bottom and top members 5 and 6 and to that end members 3 and 4 are by reason of the channel widths selected capable of completely telescoping. To facilitate the free operation of the screw 7 the ends of the arms adjacent the screw are outwardly bent to form the flares 2b and 2c on the ends of the members 2 and 2a respectively.

To insure the proper operation of the jack the arms 2 and 2a are made of sufficient length so that it is never necessary to open the arms completely since when the arms are parallel the jack has no ability to resist a lateral strain and may cause the vehicle to topple off the jack. For this purpose the jack is additionally provided with a safeguard in that the screw 7 is preferably only partially threaded so that the arms need never be spread farther than shown in Figure 2.

A plate 9 is welded or otherwise secured to the upper surface of the channel 6 which is perforated to permit the bolts 10 to pass through the plate. The nuts 11 are then 5 placed and the installation of the improved jack is completed.

The jack is actuated by the insertion of a wrench socket over the hexagonal end 7a of the screw. The wrench is also preferably 10 provided with an elongated handle and a universal joint to insure a convenient operation of the jack under all conditions. For additional convenience the socket of the wrench should be the same as that required for tire 15 nuts so that the same tool may serve both purposes.

The special utility of the construction herein described resides in the compactness which is attained since adequate clearance 20 for the vehicle is a primary requisite to the success of a device of this kind. Simplicity of construction with a resulting economy in manufacture and lightness are attained also in this manner.

25 Having thus described my invention what I claim as new and desire to secure by Letters Patent is:

1. A jack for vehicles and the like comprising a flat upper base to be secured to a 30 vehicle and having a longitudinal recess on its under side; a flat lower base having a similar recess to cooperate herewith; double toggle arms having an aggregate length in excess of the vertical movement of said jack 35 and pivoted at the ends of said upper and lower bases, one middle joint of said toggles being bored and threaded for engaging a screw having a blank end passing through the opposite middle joint, means for rotating 40 said screw whereby the toggle arms may be raised or depressed and means for preventing said arms from attaining a vertical position.

2. A jack for vehicles and the like comprising a flat upper base to be secured to a vehicle and having a longitudinal recess on its under side, a flat lower base having a similar recess to cooperate therewith; double toggle arms having an aggregate length 50 in excess of the possible vertical movement of said jack and pivoted at the ends of said upper and lower bases, one middle joint of said toggles being bored and threaded, a screw having a blank portion of greater 55 length than said upper and lower bases engaging said threaded joint and passing through the opposite middle joint and means for rotating said screw whereby the toggle arms may be raised or depressed.

60 3. A jack for vehicles and the like comprising a channel upper base to be secured to a vehicle and forming a longitudinal recess on its under side, a similar lower base of less width forming a similar recess to operate therewith and to telescope within the

same, channel arms pivoted to each of the ends of said upper base, channel arms of less width pivoted to the ends of said lower base, U-shaped members laterally pivoting the joints of said upper and lower toggle arms 70 at a common point on either side, a screw having a blank portion of greater length than said upper and lower bases, engaging threads in one of said U-shaped members and having its blank portion supported by a bearing 75 within the other, and means for rotating said screw whereby the toggle arms may be raised or depressed substantially as illustrated and described.

Signed by me this 13th day of January, 80 1931.

CHAS. A. FOYER.
